UNITED STATES PATENT OFFICE.

JOHN L. SAUNDERS AND JESSE C. SAUNDERS, OF SEDALIA, MISSOURI, ASSIGNEES OF ONE-FOURTH TO W. W. BARRETT AND ONE-FOURTH TO E. R. BARRETT, BOTH OF SEDALIA, MISSOURI.

PERMUTATION LOCK.

Application filed November 24, 1922. Serial No. 603,096.

To all whom it may concern:

Be it known that we, JOHN L. SAUNDERS and JESSE C. SAUNDERS, citizens of the United States, residing at Sedalia, in the county of Pettis and State of Missouri, have invented certain new and useful Improvements in Permutation Locks; and we do hereby declare the following to be a full, clear, and exact description of the invention, such as will enable others skilled in the art to which it appertains to make and use the same.

The present invention relates to permutation locks, and aims to provide such a lock comprising a novel construction and assemblage of the component elements whereby to enhance the efficiency and utility of the device.

As a more specific object, the invention aims to provide a tumbler device, which can, under certain predetermined requirements be removed as a unit for changing the combination, or for making adjustments, or the like.

Another object is the provision of a tumbler device whose parts are assembled together as a unit in a novel manner for operation.

A further object is the provision of a tumbler device for permutation locks in which the relatively movable tumblers have cooperative elements which, in a predetermined relation of the tumblers, are adapted to open the lock.

A still further object is the provision of a tumbler device of the kind indicated of novel construction to enable various combination changes to be made by the relative positions of the cooperative elements of the several tumblers.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a front view of the improved lock, constructed as a padlock as shown.

Figs. 2 and 3 are enlarged sectional views on the lines 2—2 and 3—3, respectively, of Fig. 1, Fig. 2 showing the tumblers as in

position for unlocking the lock, with the balls shown in dotted lines.

Fig. 4 is a section on the line 4—4 of Fig. 3, on a reduced scale, taken between the sections or plates of the body or case, portions being shown in elevation.

Fig. 5 is a view showing the parts of the tumbler device separated, partly in elevation and partly in section.

Fig. 6 is a view corresponding with Fig. 4 showing the tumblers arranged for unlocking, with the shackle in open position and turned to permit the tumbler unit or device to be removed.

The body or case of the lock, which is in the form of a padlock as shown, comprises the two sections or halves 11 placed together and constituting plates of suitable metal, said sections or plates being secured together by means of rivets 12 engaged therethrough or by other securing means. The body or case has a recess 13 opening at one side and extending through one section 11 and into the other, as seen in Figs. 2 and 3, and said body has the bores 14 and 15 between them, which are formed by providing complementary grooves in the adjacent or confronting surfaces of the sections 11. Said bores are parallel, as shown, and extend to one edge of the body, which is the top of the body as shown, and said bores terminate short of the opposite edge or bottom of the body. The bores 14 and 15 are arranged tangentially relatively to the recess 13, at opposite sides of said recesses with said bores intersecting the periphery of the recess 13, as seen in Figs. 4 and 6.

The shackle 16 has a long limb or shank 17 fitted in the bore 14 for turning and sliding movements, and the inner or lower end of said shank 17 has a head or collar 18 movable within an enlargement 19 of the bore 14 at the inner end thereof, thereby preventing the withdrawal of the shank 17 from the body, but permitting the shackle 17 to have a limited sliding movement longitudinally of the shank 17 as well as a turning movement about the axis of said shank. The opposite terminal of the shackle has a stub 20 to enter the bore 15 when the shackle 105 is closed, and an ejector pin 21 is slidable in the bore 15 to abut the stub 20, a coiled spring 22 being confined in the bore 15 between the pin 21 and bottom or inner end of said bore, for projecting the pin 21, so 110

that when the shackle 16 is released, the spring 22 in forcing the pin 21 outwardly, as seen in Fig. 6, will disengage the free end of the shackle from the case or body, so that the shackle can be swung or turned to open position, as seen in Fig. 6.

The body or case has an elongated recess 23, formed by complementary grooves or channels in the adjacent surfaces of the sections 11, and located tangentially relatively to the recess 13 at substantially right angles with the bores 14 and 15 adjacent to the upper edge of the body. A latch 24 is slideable in the recess 23 tangentially relatively to the recess 13 and tumbler device therein, and the stub 20 has a notch 25 for the engagement of one end of said latch, to hold the shackle in closed position, as seen in Fig. 4. A coiled spring 26 is confined in the recess 23 between the latch 24 and the end of the recess 23 which terminates short of the bore 14, the other end of said recess opening into the bore 15 to enable the latch to engage the shackle. The latch 24 has a lug 27 depending or projecting into the recess 13 to be operated by the tumbler device to retract the latch, for releasing the shackle, as will hereinafter more fully appear. The shank 17 and latch 24 can be readily placed between the sections 11 before they are secured together, and the pin 21 and its spring 22 are readily inserted in and removed from the bore 15 when the shackle is in open position.

35 The tumbler device or unit is fitted in the recess 13 of the body or case from one side thereof, and comprises the dials or circular index members 30, 31 and 32 which are concentric. The dial or index member 30 is a disk, while the dials or index members 31 and 32 are annular, said dials being of increasing diameters so that the face of each of them is exposed for turning and setting the tumblers of which said dials constitute parts. Said dials 30, 31 and 32 have the respective shoulders 33, 34 and 35 extending from their inner sides, and the dial 30 has the stud or boss 36 of smaller diameter than the shoulder 33 extending inwardly beyond said shoulder, while the dials 31 and 32 have the respective annular flanges 37 and 38 of smaller diameters than the respective shoulders 34 and 35 extending inwardly beyond said shoulders. The rings 40, 41 and 42 are fitted snugly on the stud 36 and flanges 37 and 38, respectively, and abut the respective shoulders 33, 34 and 35. The flange 37 and dial 31 are fitted snugly around the ring 40 and shoulder 33, with the dial 31 having its face abutting a shoulder 43 on the central tumbler member between the dial 30 and shoulder 33. In a similar manner, the dial 32 and its flange 38, constituting part of the larger or surrounding tumbler member, are fitted snugly on the ring 41 and shoulder 34

of the intermediate tumbler member, and said intermediate tumbler member has a shoulder 44 between the dial 31 and shoulder 34 against which the face of the dial 32 abuts. The three tumbler members and their rings 70 are thus fitted one on the other in concentric arrangement, and a cup-shaped retainer 45 is used for holding the parts assembled as a unit. Thus, the inner edges of the rings 40, 41 and 42 and the inner edges of the flanges 75 37 and 38 all abut the disk of said retainer 45, while the rim of said retainer snugly fits on or around the ring 42. The retainer 45 is fitted snugly in the recess 13 with the disk of said retainer bearing against the 80 back wall of the body and the rim of the retainer snugly fitting the periphery of said recess, as seen in Figs. 2 and 3. The retainer 45 is split or divided diametrically, as at 46, so that its semi-circular halves or sections 85 can be readily placed together or separated when the tumbler device or unit is removed from the body. The retainer 45 has a slot 47 to receive the lug 27 of the latch 24 when the tumbler unit is inserted into the recess 13, 90 and to also permit of the movement of the lug 27 when the latch 24 is slid. The retainer 45 and central tumbler member have a swivel connection, to hold them assembled, whereby the other tumbler members and 95 rings are held between the dial 30 and retainer 45. Thus, the disk of the retainer 45 has a central countersunk opening 48 receiving the countersunk head 49 on the end of the stud 36, thereby anchoring the central 100 tumbler member to the retainer 45. When the tumbler members and rings are assembled, the halves or sections of the retainer 45 can be readily brought together around the ring 42, to engage said sections of the retainer with the head 49, and when the tumbler unit is inserted in the recess 13, the sections of the retainer are prevented from 105 being separated, thereby holding the central tumbler member assembled with the retainer by a swivel anchor pivot. This enables the central tumbler member to be rotated, and the other tumbler members can be rotated around the central tumbler member. 110

In order to establish a correlation of the tumbler members, the rings 40, 41 and 42 are provided with the respective apertures 50, 51 and 52 in which the balls 53, 54 and 55 are disposed, said balls constituting the 115 cooperative elements or members of the tumblers. The stud 36 has an annular series of depressions or recesses 56 in which the ball 53 is seatable, and the flanges 37 and 38 have the annular series of apertures 120 57 and 58, respectively, for the engagement of the balls 54 and 55. The aperture 50 of the ring 40 can be brought into registration with any of the recesses 56 of the stud 36 by 125 turning the ring 40 on said stud, so that the 130

ball 53 can be seated in any one of said recesses, for changing the angular position of the ball 53 with reference to the dial 30, for changing the combination. Similarly, the 5 apertures 51 and 52 of the rings 41 and 42, respectively, can be brought into registration with any of the respective apertures 57 and 58, to change the relative angular positions of the balls 54 and 55 with reference to the respective dials 31 and 32, for combination changes. The balls can thus be positioned at different points around the peripheries of the tumbler members, and in order to prevent the angular or rotary 10 placement of the rings 40, 41 and 42 relatively to the corresponding dials 30, 31 and 32, while the parts are assembled, the outer or forward edges of said rings have dowels 15 60 projecting therefrom to enter holes 61 in the shoulders 33, 34 and 35. When the rings are slipped on the tumbler members, the apertures of the rings can be brought into registration with the desired recess 56 and apertures 57 and 58, and the dowels 60 20 enter the corresponding holes 61. The rings 40 and 41 have the circumferential or annular grooves or channels 62 and 63, respectively, in which the balls 54 and 55 are adapted to travel when the tumblers are 25 turned relatively to one another, and the rim of the retainer 45 has an inner annular groove or channel 64 in which the ball 55 can travel, when said ball projects beyond the circumference of the ring 42. 30 In order that the tumbler device or unit is properly positioned in the body or case, the disk of the retainer 45 has an aperture 65 receiving a lug or dowel 66 carried by the back of the body. 35 The tumbler device is held secure in the body by the shank or limb 17 of the shackle and the ejector pin 21, it being noted that said shank 17 and pin 21 projects slightly 40 into the recess 13 at opposite sides, due to the cutting of the wall of the recess 13 by the bores 14 and 15. The rim of the retainer 45 is provided at opposite sides with the notches or slots 67 receiving the shank 45 17 and pin 21 which thereby lock or secure the tumbler unit in the recess 13. The shank 17 is provided with a notch or cut-away portion 68 so arranged, that when the shackle has its free terminal withdrawn from the 50 body and turned to a predetermined position, as seen in Fig. 6, the notch 68 registers with the recess 13, to permit the tumbler unit to be withdrawn from the recess 13 past the shank 17, and when the pin 21 is also withdrawn from the corresponding notch or slot 67, the tumbler unit or device can be withdrawn from the recess 13, the slot 47 of the retainer 45 opening rearwardly for the passage of the lug 27 of the latch 24. In 55 this way, the tumbler unit can be readily withdrawn from the body or case when the lock is opened and the shackle properly positioned and the pin 21 withdrawn. The sections of the retainer 45 can then be separated, which permits the tumblers to be separated, for changing the combination. 60 The combination is changed by turning the rings 40, 41 and 42 relatively to the dials to bring the apertures of the rings into registration with different recesses 56 and apertures 57 and 58, respectively, of the dials or 65 tumbler members, as will be apparent. When the tumbler device is assembled and inserted in the recess or socket 13, the pin 21 being inserted in the bore 15 and the shackle 16 turned or slid from its position as seen in 70 Fig. 6, will thereby securely lock the tumbler unit in the body. 75 When the shackle 16 or other member controlled by the lock, is in closed or locked position, with the latch 24 engaging it, as 80 seen in Fig. 4, and the combination destroyed, so as to disarrange the tumblers, the balls 53, 54 and 55 are out of radial alignment with reference to the tumbler unit, as seen in Fig. 4. The ball 54 is movable 85 radially in the aperture 51 and corresponding aperture 57 to enter either the groove 62 or the groove 63, and the ball 55 is movable radially in the aperture 52 to enter either the groove 63 or the groove 64, and the ball 90 55, which is used to retract the latch 24, cannot be made effective or positioned to retract the latch, unless the tumblers are turned to a relative predetermined position, to bring those graduations in radial alignment or registration, according to the positions of the balls with reference to the 95 graduations of the dials. When the tumblers are set for the particular combination, 100 the balls 53, 54 and 55 are brought in radial alignment. Thus, the ball 53 projecting into the groove 52, will be in the path of the ball 54, so that when the ball 54 is moved into radial alignment with the ball 53, the ball 105 54 is forced radially outward by cam action, to project into the groove 63, and the ball 55, when brought into radial alignment with the ball 54, will likewise be forced outwardly from the groove 63 by cam action to project 110 into the groove 64. The ball 55 is thus projected into the groove 64 into the path of the lug 27, and when the tumblers are in this position and turned (clock-wise as seen in Fig. 6) the ball 55 in engaging the lug 27 115 will retract the latch 24, thereby releasing the shackle 16. The ejector pin 21 will therefore eject the free end of the shackle from the body, thereby opening the lock. The lock is again readily closed by pushing 120 the shackle to closed position, and the pin 21 is forced back into the bore 15, and the latch 24 snaps into engagement with the shackle. 125 Haying thus described the invention, what 130 is claimed as new is:—

1. In a lock, relatively movable tumblers, means movable with the tumblers and arranged to move relatively to the tumblers when the tumblers are brought to a predetermined relative position, and latching means arranged to be moved with the tumblers by said means when said means are moved relatively to the tumblers.
2. In a lock, relatively movable tumblers, means movable with and carried by said tumblers and arranged to be forcibly moved relatively to the tumblers when the tumblers are brought to a predetermined relative position, and latching means arranged to be engaged by the firstnamed means when the firstnamed means are moved relatively to the tumblers so as to move the lastnamed means with the tumblers.
3. In a lock, relatively movable tumblers, a member to be operated by said tumblers, and means carried by the tumblers adapted to be projected from the tumblers when the tumblers are brought to a predetermined relative position to engage said member for moving it with the tumblers.
4. In a lock, relatively movable tumblers, a member to be moved by said tumblers, and cooperable elements movable with the tumblers and arranged to move relatively to the tumblers, when the tumblers are brought to a relative predetermined position, to establish a connection between said member and tumblers for moving said member with said tumblers.
5. In a lock, relatively movable tumblers, a member to be operated by the tumblers, and means carried by the tumblers and arranged, when the tumblers are brought to a predetermined relative position, to move relatively to the tumblers and make connection with said member for moving it with the tumblers.
6. In a lock, relatively movable tumblers, elements movable with said tumblers and arranged to be brought into alinement when the tumblers are brought to a predetermined relative position, said elements being movable relatively to the tumblers when said elements are in alinement, and latching means arranged to be moved by said elements when they are in alinement and moved relatively to the tumblers.
7. In a lock, relatively movable tumblers, elements movable with said tumblers and arranged to be brought into alinement and contact, and arranged to move relatively to the tumblers when in alinement to project one of said elements, and latching means movable with the tumblers by said projected element when the elements are in alinement and moved relatively to the tumblers.
8. In a lock, relatively movable tumblers, elements movable with the tumblers and arranged to contact when the tumblers are brought to a predetermined relative position and to be forcibly moved relatively to the tumblers by such contact, and means arranged to be engaged by one of said elements when said elements are moved relatively to the tumblers.
9. In a lock, relatively movable tumblers, balls movable with the tumblers to be brought into alinement and arranged to contact by cam action when brought into alinement for projecting one of said balls, and latch means controlled by the projected ball.
10. In a lock, relatively movable tumblers, balls movable with said tumblers to be brought into alinement, and arranged to contact by cam action when brought into alinement for projecting one of the balls, and a member adapted to be operated by said projected ball.
11. In a lock, concentric relatively rotatable tumblers, an element movable with each tumbler, said elements being arranged to aline radially of the tumblers when the tumblers are turned to a predetermined position relatively to one another, and means controlled by said elements when in alinement.
12. In a lock, concentric relatively rotatable tumblers, an element movable with each tumbler, said elements being arranged to aline radially of the tumblers and to move radially of the tumblers when alined, and means controlled by said elements when moved relatively to the tumblers.
13. In a lock, concentric relatively rotatable tumblers, a member to be moved by said tumblers, an element movable with each tumbler, said elements being arranged to aline in a predetermined relative position of said tumblers, and said elements being movable relatively to the tumblers when said elements are alined, for the engagement of said member by one of said elements to move said member with the tumblers.
14. In a lock, concentric relatively rotatable tumblers, a ball movable with each of said tumblers, said balls being adapted to be alined radially of the tumblers when the tumblers are turned to a predetermined position relatively to one another, and means controlled by said balls when so alined.
15. In a lock, concentric relatively rotatable tumblers, balls movable separately with said tumblers to be alined radially of said tumblers for projecting one ball by cam action between the balls, and latch means operable by said projected ball.
16. In a lock, relatively movable tumblers, elements movable with said tumblers to be brought into alinement, and means controlled by said elements when in alinement, each tumbler having a series of apertures for receiving the corresponding element to change the combination.
17. In a lock, concentric relatively rotatable tumblers, elements movable with said

tumblers to align radially of said tumblers, means controlled by said elements when so aligned, each tumbler having an annular series of apertures for receiving the corresponding elements to change the combination.

18. In a lock, a tumbler having relatively adjusted parts with apertures to register in different relative positions of said parts, and 10 a lock controlling element to be disposed in registering apertures for moving one part with the other and movable in said apertures relatively to both of said parts.

19. In a lock, a tumbler having relatively movable parts, one part having a series of apertures and the other part an aperture to register with said apertures in the different relative adjustments of said parts, a lock controlling element to be disposed in 20 the registering apertures for moving one part with the other and movable in said apertures, and means controlled by said element when moved in said apertures.

20. In a lock, a rotatable tumbler having 25 parts adapted to be turned to different positions relatively to one another and provided with apertures adapted to register in the different positions of said parts, a lock controlling element to be disposed in registering apertures in said parts for turning one part with the other, means for moving said element in said apertures, and means controlled by the movement of said element in 30 said apertures.

35. 21. In a lock, a rotatable tumbler including a tumbler member and a ring fitting it, said ring and member being rotatable relatively to one another for changing the angular position, one of said parts having a 40 series of apertures and the other an aperture to register with said apertures in the different relative positions of said member and ring, and a lock controlling element to be movably disposed in the registering apertures.

50. 22. In a lock, concentric relatively rotatable tumblers each having a circular portion with an annular series of apertures and a ring fitting said portion for rotatable adjustment relatively thereto and having an aperture to register with the aforesaid apertures, and an element for each tumbler to be disposed in the registering apertures of the ring and portion of the tumbler, said 55 elements being cooperable when in radial alinement, and means controlled by said elements when in radial alinement.

60. 23. In a lock, concentric relatively rotatable tumblers each including a circular portion and a ring fitted thereon for rotary adjustment, said portion and ring having apertures adapted to register in different relative positions of said portion and ring, said portions and rings of the several tumblers sur-

rounding one another, balls disposed in the 65 registering apertures of the several tumblers to engage by cam action when aligned radially, said rings having annular grooves in which the balls are movable to engage one another by the relative rotation of the 70 tumblers, and means controlled by said balls when radially aligned.

24. In a lock, tumblers fitting one another, and a retainer receiving and holding said tumblers, one tumbler having an index portion 75 at one end, the other end of said tumbler and retainer having portions to interengage for holding them assembled, and the other tumblers being disposed around the aforesaid tumbler between said index portion and 80 retainer.

25. In a lock, rotatable tumblers located concentrically one around the other, and a retainer receiving and holding said tumblers, the central tumbler having an index 85 portion at one end, the other end of the central tumbler and retainer having portions to interengage for holding them assembled, and the surrounding tumblers being disposed between said index portion and 90 retainer.

26. In a lock, a set of tumblers, and a retainer receiving and holding said tumblers, one tumbler having a portion to be engaged by the retainer, the retainer being composed of sections to be brought together to receive and hold the tumblers therein and to engage said sections with said portion for anchoring said tumbler to the 95 retainer, the other tumblers being held between said tumbler and retainer.

27. In a lock, concentric rotatable tumblers surrounding one another, and a retainer for receiving and holding said tumblers, one tumbler having an index portion at 105 one end, the other end of said tumbler and retainer having portions engaging one another with a swivel connection, the other tumblers being held between said tumbler and 110 retainer.

28. In a lock, concentric relatively rotatable tumblers, and a retainer for receiving and holding said tumblers, one tumbler having a swivel connection with the retainer for holding them assembled, the other tumblers being held between said tumbler and 115 retainer, said retainer being composed of sections to be separated for disconnecting the retainer and firstnamed tumbler.

29. In a lock, concentric relatively rotatable tumblers, a cup-shaped retainer for receiving and holding said tumblers therein, said retainer having an aperture, one tumbler having a portion to fit in said aperture for swivelling and anchoring said tumbler to said retainer, the other tumblers being held between said tumbler and retainer, and the retainer being composed of separable 120 125

sections to detach the firstnamed tumbler and retainer.

30. In a lock, a body, a retainer fitted in said body and composed of separable sections held together while in the body, and tumblers in said retainer, one tumbler and said retainer having portions engaging one another to hold the tumblers and retainer assembled while the sections of the retainer are held together in the body.

31. In a lock, concentric relatively rotatable tumblers, and a retainer, a central tumbler having swivel portion and the retainer having a portion to engage said swivel portion for anchoring said tumbler to the retainer with the swivel connection, said retainer comprising separable sections for disconnecting said retainer and tumbler, and the surrounding tumblers being confined between the aforesaid tumbler and retainer.

32. In a lock, concentric relatively rotatable tumblers, and a retainer, the central tumbler having a swivel portion and the retainer having an aperture receiving said portion for anchoring said tumbler to the retainer with a swivel connection, said retainer comprising separable sections for disconnecting said retainer and tumbler, the tumblers having shoulders abutting one another and the surrounding tumblers abutting said retainer.

33. In a lock, a body, a retainer fitted in the body, and tumblers assembled with the retainer, said retainer and one tumbler having interengaging portions holding the tumblers and retainer assembled, and said retainer comprising separable sections for disconnecting the retainer and tumblers when the retainer is removed from the body.

34. In a padlock, a body, a tumbler device removably fitted in said body, and a shackle having a shank fitted in the body, said shackle being under the control of said device, said device having a portion engaging said shank for holding said device in the body, and said shank having a notch at one side permitting the removal of said device through said notch when the shackle is

opened and brought to a predetermined position.

35. In a padlock, a body having a recess, a tumbler device fitted removably in said recess, and a shackle having a shank fitted in the body tangentially relatively to said recess, said device having a notch engaged by said shank for holding said device in the recess, and the shank having a notch at one side to be positioned, when the shackle is opened, to permit said device to be removed from the recess through said notch.

36. In a padlock, a body having a recess, a tumbler device fitted removably in said recess, a shackle having a shank fitted in the body, a spring pressed ejector slidable in the body for disengaging the shackle from the body, said shank and pin being at opposite sides of said recess, said device having opposite notches engaging said shank and pin, and said shank having a notch to register with said recess when the shackle is opened and properly positioned, so that when the shackle is so positioned and said pin removed, said device can be removed from the recess.

37. In a padlock, a body comprising a pair of sections secured together having grooves at their adjacent surfaces providing bores and a recess extending to one bore, one bore having an enlarged portion, a shackle having a shank at one end fitted in said bore for sliding and turning movement, said shank having a flange in said enlarged portion to limit the sliding movement of said shank, the other end of the shackle having a portion to enter the other bore, and a latch slidably in said recess to engage the last-named portion.

In testimony whereof we have signed our names to this specification in the presence of two subscribing witnesses.
